ARTICLESDiane E. Christopher and John H. Christopher,
Wakefield, Mass.

Application September 9, 1949, Serial No. 4,932

Term of patent 7 years

(Cl. D58—2)

To all whom it may concern:

Be it known that we, Diane E. Christopher and John H. Christopher, citizens of the United States, residing at Greenwood, Wakefield, in the county of Middlesex and Commonwealth of Massachusetts, have invented a new, original, and ornamental Design for Bag for Clothespins or Other Articles, of which the following is a specification, reference being had to the accompanying drawing, forming a part thereof:

In the drawing:

The dotted lines shown in the drawing are for illustrative purposes only.

We claim:

The ornamental design for a bag for clothespins or other articles, as shown and described.

DIANE E. CHRISTOPHER.
JOHN H. CHRISTOPHER.
